UNITED STATES PATENT OFFICE.

FREDERICK K. NORTH, OF CHICAGO, ILLINOIS, ASSIGNOR TO ILLINOIS MALLEABLE IRON CO., OF CHICAGO, ILLINOIS, A CORPORATION OF ILLINOIS.

ANCHOR-PLATE ASSEMBLY.

Application filed June 28, 1926. Serial No. 118,877.

The present invention relates to anchor plate assemblies.

More particularly the present invention relates to plate assemblies for underlying railroad rails, being disposed between said rails and the supporting cross ties.

An object of the present invention is to provide an anchor plate assembly for abutting the two sides of a railroad cross tie and adapted to firmly grip the rail, whereby to prevent creeping of said rail in both longitudinal directions.

A further object is to provide anchor plate means adapted to prevent creepage of the rail in both directions which anchor plate means is simple to install and to adjust.

A further object is to provide an anchor plate assembly for preventing creeping of the rail in both directions which anchor plate assembly is made up of two sections which may be identical in size and shape, whereby to simplify the matter of stocking said assemblies.

Further objects will appear as the description proceeds.

Referring to the drawings—

Figure 1 is a view of a railroad rail having cooperatively associated therewith a railway cross tie and an anchor plate assembly embodying the principles of the present invention;

Figure 2 is a top plan view of the structure shown in Figure 1;

Figure 3 is a sectional view taken along the plane indicated by the arrows 3—3 of Figure 2;

Figure 4 is a sectional view taken along the plane indicated by the arrows 4—4 of Figure 2;

Figure 5 is a view similar to Figure 1 but showing a modified form of the anchor plate assembly illustrated in Figure 1;

Figure 6 is a top plan view of the structure shown in Figure 5; and

Figure 7 is a sectional view taken along the plane indicated by the arrows 7—7 of Figure 6.

Referring first to the embodiment of the invention disclosed in Figures 1 to 4, the anchor plate assembly comprises the two complementary members 10—10, which may be identical with one another. Each of the members 10 comprises a flat plate portion 11 adapted to lie upon the upper surface of

the cross tie 12 and to support the rail 13. 55

The plate portions 11—11 are provided with spike holes 14 for receiving the spikes which secure the rail 13 to said cross tie 12.

Integral with each of the plates 11 is a rail gripping portion 15 adapted to cooperate with a rail gripping member 16. The portion 15 and the member 16 are complementary members having the hooked over portions 17 and 18, respectively. The hooked over end portions 17 and 18 are 60 adapted to hook over the opposite flanges 19—19 of the rail 13. The members 10—10 and the member 16 may be composed of malleable iron, steel, or other tough material capable of withstanding the shocks encountered in railroad service. The portion 15 is provided with the downwardly extending portion 20, which provides a seat 21 for the head 22 of a bolt 23. Said bolt 23 normally occupies a position inclined to the horizontal 75 and to the vertical, for which reason the seat 21 should be arranged in a corresponding angular position. The downwardly extending portion 20 is provided with the slot 24 for the reception of the bolt 23, said slot 80 being bounded longitudinally of the rail 13 by the wall 25, that face of the wall 25 which is adjacent to the plate portion 11 being substantially flat and arranged in substantially right-angular relationship with the under 85 side of said plate portion 11. The member 16 is provided with the downwardly extending portion 26 for the reception of the bolt 23. Said downwardly extending portion 26 of the member 16 is provided with the slot 90 27 in which the bolt 23 is disposed. A nut 28 and lock washer 29 serve to hold the member 16 and the portion 15 in cooperative gripping relationship with the flanges of the railway rail. The downwardly extending 95 portion 26 of the member 16 is provided with flat walls 30, normally disposed in right-angular relationship with the bottom side of the plate 11. For the purpose of providing a strong leverage action, the portion 15 of the member 10 and the member 16 are formed to provide portions adapted to engage the under side of the rail at lines 31—31 relatively distant from the side edges 100 of the flanges of said rail.

The flat faces of the downwardly extending portions 20 and 26 are adapted to abut against the side of the cross tie 12. By

reason of the fact that the portion 15 and the member 16 have gripping engagement with the flanges of the rail, and by reason of the fact that the bolt 23 exerts a leverage action upon said portion 15 and member 16 about the lines 31-31, the net effect is a very firm gripping engagement between the flanges of the rail 13 on the one hand and said portion 15 and member 16 on the other hand. The angular position of the bolt 23 has the further advantage that a workman may effectually tighten said bolt in an expeditious manner. In practice, a workman may proceed along the track with a socket wrench and turn down the nuts 28 upon the bolts 23, working rapidly and with assurance that a non-slipping engagement with the rail will be accomplished.

Referring now to the structure illustrated in Figures 5, 6 and 7, a modified form of plate is employed for supporting the rail 13 upon the cross tie 12. According to the embodiment illustrated in Figures 5 to 7, each of the bed plates 32 has a width transversely of the rail 13 substantially greater than the width of the flanges of said rail, whereby spikes may be inserted through appropriate holes 14 in said bed plate 32 for securing the two flanges of said rail in position upon the cross tie. The dimension of the bed plate 32 in a direction longitudinally of the rail is considerably shorter than the plate 11 illustrated in Figures 1 to 4, inclusive, being slightly less than half of the width of the cross tie 12. The plate 32 of each of the members of the anchor plate shown in Figures 5 to 7 may be provided with the portion 15, which may take the form described above in connection with Figures 1 to 4, inclusive. Each portion 15 may have cooperating therewith the member 16, which may be identical with the corresponding member 16 in the structure shown in Figures 1 to 4.

It will be clear that the embodiments of the present invention shown in the drawings will effectually prevent creepage of the rail in either direction by reason of the engagement of the downwardly extending part of the portion 15 and the downwardly extending part of the cooperating member 16 with the side of the tie toward which creepage tends to occur. By reason of the very secure locking engagement of the portion 15 and the member 16 with the rail, this function of preventing creepage in both directions is accomplished even if said spikes should work loose, the anchor plates disclosed being operative to effectually hold the rail from creepage.

The illustrated embodiments of the present invention have been chosen merely for purpose of illustration and should not be considered in a limiting sense. Many modifications will occur to those skilled in the

art. It is intended to cover all such modifications that fall within the scope of the appended claims.

What is claimed is—

1. An anchor plate assembly for securing a railroad rail upon a tie and to hold said rail against creepage relative to said tie, comprising a pair of members each including a bed plate for said rail and a rail gripping portion integral with said bed plate, and rail gripping members adapted to cooperate with said rail gripping portions, said rail gripping portions and members being adapted to be disposed in abutting relationship with the sides of a railroad tie.

2. An anchor plate assembly for securing a railroad rail upon a tie and to hold said rail against creepage relative to said tie, comprising a pair of members each including a bed plate for said rail and a rail gripping portion integral with said bed plate, and rail gripping members adapted to cooperate with said rail gripping portions, said rail gripping portions and members being adapted to be disposed in abutting relationship with the sides of a railroad tie, said first mentioned members being substantially identical with each other and said rail gripping members being substantially identical with each other.

3. Rail anchoring means comprising a pair of plate members each having a flat portion adapted to underlie a railroad rail and each having a second portion adapted to hook over a flange of a railroad rail, a rail gripping member adapted to cooperate with each of said second portions, and a bolt and nut cooperating with each of said second portions and its corresponding rail gripping member, each of said bolts occupying a position angularly of the rail engaging positions of said members.

4. Rail anchoring means comprising a pair of members each having a portion adapted to underlie a railroad rail and a second portion adapted to hook over a flange of said railroad rail, a rail gripping member adapted to cooperate with each of said second portions, each of said second portions and its corresponding rail gripping member being provided with a part adapted to abut the bottom of said railroad rail at regions relatively distant from the side edges of said flanges, the hooking parts of said second portions and members and the rail bottom abutting parts of said second portions and members lying approximately in the same plane, and a bolt cooperatively associated with each of said rail gripping members and its associated second portion, said bolts being arranged angularly of said plane and having abutting cooperation with their corresponding second portions and members.

5. In combination, a railroad rail having

flanges on its opposite sides, rail anchoring means comprising a pair of members each provided with a plate adapted to underlie said rail and each provided with a rail gripping portion, and a pair of rail gripping members each adapted to cooperate with one of said portions, said members and portions adapted to hook over the side edges of said flanges, and a bolt having cooperative relation with each of said portions and its corresponding member and lying in angular relationship with the bottom of said rail for holding said portions and members in tight gripping relationship to said rail.

6. In combination, a railroad rail having a bottom flange, a pair of members each having a plate adapted to underlie said rail and a portion adapted to hook over a side edge of said flange, a rail gripping member adapted to cooperate with each of said portions, each of said members and portions being provided with a part adapted to abut the under side of said rail, said hooked over parts and said bottom abutting parts being substantially in the same plane, and a bolt lying at an angle to the bottom of said rail and having a nut presented laterally of said rail.

7. In combination, a railroad rail having a bottom flange, a pair of members each comprising a plate for underlying said rail and a portion having a hooked over flange engaging part and a part adapted to abut the bottom of said rail, a rail gripping member cooperatively associated with each of said portions and having a part adapted to abut the bottom of said rail, and bolt means disposed angularly with reference to the base of said rail, said bolt means cooperating with said members and portions to exert a leverage action upon said portions and members about said bottom abutting parts as fulcrums.

8. In combination, a railroad rail having a bottom flange, a pair of members each comprising a plate for underlying said rail and a portion having a hooked over flange en-

gaging part and a part adapted to abut the bottom of said rail, a rail gripping member cooperatively associated with each of said portions and having a part adapted to abut the bottom of said rail, and bolt means disposed angularly with reference to the base of said rail, said bolt means cooperating with said members and portions to exert a leverage action upon said portions and members about said bottom abutting parts as fulcrums, said bolt means being provided with nut means presented laterally of said rail.

9. Rail anchoring means comprising a pair of members each having a plate for underlying a railroad rail and each having a portion adapted to engage the upper side of a flange of a railroad rail and the bottom of said rail, and a pair of rail gripping members each having cooperative relationship with one of said portions, each of said rail gripping members being adapted to engage the upper side of a flange of said rail and the bottom of said rail, and means cooperating with each of said members and its cooperating portion for exerting a leverage action upon said members reacting between the flange engaging and the bottom engaging portions of said members, said means including bolts disposed angularly with respect to the bottom of said rail.

10. In combination, a railroad rail, anti-creeping means cooperating therewith comprising a pair of members each having a portion for hooking over the side edge of the flange of said rail, each of said portions being adapted to abut the bottom of said rail, each of said members including a plate integral with said portion adapted to underlie said rail, and rail gripping members cooperating with said portions, and leverage means for causing said members and portions to grip said rail, each of said portions being provided with a part adapted to engage the side of a railroad tie.

Signed at Chicago, Illinois, this 24th day of June, 1926.

FREDERICK K. NORTH.
